UNITED STATES PATENT OFFICE.

CHARLES E. REDDIG, OF RICHMOND HILL, NEW YORK, ASSIGNOR TO WESTERN ELECTRIC COMPANY, INCORPORATED, OF NEW YORK, N. Y., A CORPORATION OF NEW YORK.

CLOTHES-IRONING MACHINE.

Application filed October 29, 1920. Serial No. 420,471.

To all whom it may concern:

Be it known that I, CHARLES E. REDDIG, a citizen of the United States, residing at Richmond Hill, Long Island, in the county 5 of Queens, State of New York, have invented certain new and useful Improvements in Clothes-Ironing Machines, of which the following is a full, clear, concise, and exact description.

10 This invention relates to clothes ironing machines of the type characterized by an ironing roll and a heated shoe cooperating therewith. The general object of the invention is to provide new and improved 15 means for moving the shoe with reference to the ironing roll, whereby insertion of articles to be ironed is facilitated.

While the invention is not limited to use with any particular design of ironing machine, it is herein shown and described as applied to the ironing machine which forms the subject of my co-pending application for patent, Serial No. 402,848, filed August 11, 1920.

25 Referring to the drawings, Fig. 1 is a side elevation, partly in section, of one embodiment of my invention; and Fig. 2 is a side elevation, partly in section, with a portion of the shoe and roll cut away to show 30 the elements of the hand operated mechanism.

Referring to both Fig. 1 and Fig. 2, the various parts of the ironing machine are supported by frames, one of which 35 3 is shown, these frames being rigidly connected together by pipes which are threaded near their ends and carry nuts 4 which cooperate with the outsides and insides of the frames. Supported by the 40 frames 3 are a feed table 5, a delivery table 6 and a pivoted delivery board 7. The ironing roll 8, which may be of the split cylinder type is covered with a layer 45 of fabric or felt in the usual manner, and is rigidly secured to a shaft 9 which is mounted in fixed bearings in the frames and is driven in any suitable manner. As roll 8 is of the split cylinder type, the inner end of the covering material 50 made be clamped as shown at 36. Cooperating with the ironing roll 8 is an ironing shoe 10 of any suitable form or kind, this shoe being heated by a gas burner 12 which extends through it. Projecting from 55 the bottom of the shoe 10 at each end there-

of are brackets 13 which at their bottom are provided with elliptical holes into which project pins 14 mounted in the main frames. By thus making the pivotal mountings of the shoe 10 loose, the ironing surface of the 60 shoe 10 is permitted to adapt itself to the contour of the ironing roll 8.

The shoe 10 is yieldingly and removably held in engagement with the ironing roll 8 by means which will now be described. 65 Pivottally mounted on bolts 16 extending from the inside of each of the main frames 3, are two cams 17 located respectively between opposite ends of the shoe 10 and the adjacent frame. These cams 17, which may 70 be of the form best shown in Fig. 2, have extending arms 19 connected by a bar which may be grasped by the operator and by which the cams may be moved in unison. At each side of the machine is a spring 20 through 75 which extends a rod 21 carrying a head 22 engaged by one end of said spring 20. The other end of the rod 21 is bent and projected into a hole in a lug 24 projecting from one edge of the cam 17. Near its middle 80 portion, the rod 21 carries a loose collar 25 which is engaged by the spring 20; and rod 21 also carries a collar 26 rigidly secured to said rod. The rod 21 at the portion between the collars 25 and 26 passes freely 85 through a hole in a lug 27 secured to a projection from the shoe 10. Rotatably mounted on the outer end of the lug 27 is a roller 28 adapted to cooperate with the edge of the cam 17. With this construction, it will be obvious that when the cams 90 are in position shown in the drawings, the springs 20 force the collars 25 against the lugs 27 thereby holding the shoe 10 in contact with the ironing roll 8; and that 95 when the cams are moved to other positions they move and hold the shoe 10 away from the ironing roll 8 to different distances.

The construction so far described is the same as that shown in my co-pending application hereinbefore mentioned. The foot operable means, which is capable of moving the shoe away from the ironing roll in order to facilitate the insertion of articles to be ironed, will now be described. In the embodiment shown in Fig. 1, this foot operable means is arranged to move the shoe 10 without moving the cams 17.

The foot operable means comprises arms 30 cooperating with the shoe 10 and prefer- 110

ably integral with the brackets 13 at each end of the shoe, said arms at their ends being connected to a treadle located beneath the ironing roll and shoe. This treadle may 5 comprise two levers 31 rigidly mounted on one of the pipes 4^a extending between and rotatable in the main frames 3; said levers being connected at their outer ends by a rod or pipe 32 adapted to be engaged by the 10 foot of the operator. Each of the levers 31 is connected to the arm 30 above it by means of a flexible connection, such as a wire rope 33. With this construction, it will be obvious that depression of the lever will cause 15 the shoe 10 to move slightly away from the ironing roll 8, against the tension of the springs 20, thereby facilitating the insertion of articles to be ironed.

It will be obvious that with either embodiment of the invention, the hands of the operator are left free to manipulate the clothes to be ironed, even when it is necessary to move the shoe away from the ironing roll to facilitate the inserting operation.

25 What is claimed is:

1. In an ironing machine, the combination of a frame, an ironing roll journalled therein, a shoe cooperating with said ironing roll, spring means for yieldingly holding said shoe in cooperative engagement with said roll, cam members secured to said frame and said shoe respectively and adapted when in one position to permit the shoe to be pressed against the roll and in other 30 positions to move and hold the shoe away from the ironing roll at different and comparatively large distances to permit the ready insertion of pieces to be ironed, and auxiliary means acting directly upon said 35 shoe for moving said shoe slight distances away from the roll against the tension of 40

said spring means, said auxiliary means effecting a separation of said cam members.

2. In an ironing machine, a frame, an ironing roll journalled therein for rotation, 45 a shoe cooperating with said roll, spring means for yieldingly holding said shoe in cooperative engagement with said roll, co-acting control members positioned between the shoe and said spring means and operating directly upon said shoe for separating said shoe from said roll by a comparatively large space to permit the ready insertion of pieces to be ironed, and auxiliary control means having a positive engagement with 50 both said shoe and said frame and effective, when operated, to separate the shoe from said roll slight distances against the tension of said spring means and when released to allow the spring means again to control 55 the engagement of the shoe with the roll.

3. In an ironing machine, the combination of a frame, an ironing roll journalled therein, a shoe cooperating with said ironing roll, spring means for yieldingly holding 60 said shoe in cooperative engagement with said ironing roll, cam members secured to said frame and said shoe respectively and adapted when in one position to permit the shoe to be pressed against the roll and in other 65 positions to move and hold the shoe away from the ironing roll at different distances, and auxiliary means also acting on said shoe for separating said roll and shoe, and the cam members respectively secured 70 to said frame and said shoe against the tension of said spring means.

In witness whereof, I hereunto subscribe my name this 25th day of October A. D., 1920.

CHARLES E. REDDIG.
